UNITED STATES PATENT OFFICE.

CLINTON A. HAGADONE, OF CHICAGO, ILLINOIS, ASSIGNOR TO INTERNATIONAL HARVESTER COMPANY, A CORPORATION OF NEW JERSEY.

MOLDING-MACHINE.

No. 805,134.

Specification of Letters Patent.

Patented Nov. 21, 1905.

Application filed June 16, 1905. Serial No. 265,582.

To all whom it may concern:

Be it known that I, CLINTON A. HAGADONE, a citizen of the United States, residing at Chicago, in the county of Cook and State of Illinois, have invented certain new and useful Improvements in Molding-Machines, of which the following is a specification, reference being had to the accompanying drawings, forming a part thereof.

10 My invention relates to molding-machines, and particularly to that type called "turn-over" machines, wherein the pattern-carrier is supported upon an arm that is adapted to swing through a vertical arc of one hundred 15 and eighty-degrees, more or less; and it consists in a spring counterbalancing mechanism connected with said arm and designed to accommodate itself to the various positions the arm may assume, the compensating features 20 of which mechanism effectually maintain a proper counterpoise between the weight and said mechanism as the arm is moved from side to side, the object of the invention being to improve the construction of the 25 counterbalancing mechanism in a manner to provide a better balancing or counterpoise for the moving parts. I attain this object by the mechanism illustrated in the accompanying drawings, in which—

30 Figure 1 is a side elevation of a molding-machine frame and swinging arm, the latter being shown in a horizontal position with the counterbalancing mechanism connected therewith. Fig. 2 represents the same parts 35 with the swinging arm in a vertical position. Fig. 3 is a plan view of the counterbalancing mechanism. Fig. 4 is a vertical section on line A B of Fig. 3, and Figs. 5, 6, 7, 8, 9, 10, and 11 are detached details of parts of the 40 counterbalancing mechanism.

Similar characters refer to similar parts throughout the several views.

1 represents the bed-frame of the machine, supported by the legs 2.

45 3 and 4 are vertically-arranged arms secured to the bed-frame, and 5 is a swinging arm pivotally mounted at the upper ends of the vertical arms and to which the pattern-carrying frame and associated parts are connected in any desired manner. The rear end of the arm 5 projects beyond its pivotal connection, and connected thereto is a chain or other flexible member 6, that passes downward below a sheave 7, journaled on one of

the frame members and outward and over a 55 sheave 8, journaled on a cross-rod 9 at one end of the bed-frame and inward to one end of a link 10, to which it is adjustably connected by means of a turnbuckle 11. The opposite end of the link 10 is pivotally connected with the lower end of a two-armed compensating lever 12, having its arms disposed at substantially right angles with each other, that is pivotally mounted at its upper end upon a cross-rod 13, forming part of the 60 frame of the machine and having one end pivotally connected with the link 12. Intermediate its ends is a link 14, having a cross-head 15 at its opposite end and having the reduced portions 16 and 17 at opposite ends 65 thereof. Pivotally mounted on said reduced ends are hooks 18 and 19, and 20 and 21 are flexible members having one end engaging the hooks and extending outward and over sheaves 22 and 23, journaled at opposite ends 70 of a frame member 24 at the opposite end of the bed-frame and having their opposite ends connected with adjustable eyebolts 25 and 26, that are screw-threaded to engage with screw-threaded nuts 27 and 28. The nuts are 75 grooved or threaded in a manner to engage with the coils of one end of counterbalancing-springs 29, that have their opposite ends secured to the cross-rod 9. By reason of the threaded connection of the nuts with the 80 coils of the springs they may be adjusted thereon in a manner to increase or decrease the effective power thereof, according to the 85 number of coils brought into active operation, and by means of the screw-threaded eyebolts and the turnbuckle the operative 90 length of the flexible member may be adjusted. The adjustments, as described, are designed to compensate for the difference in 95 weight of the various patterns and associated parts that may be carried by the swinging arm within certain limits. The arm 5 may be moved in either direction from a vertical to a horizontal position and the counterbalancing mechanism remain equally effective, 100 the construction of the counterbalancing mechanism being such as to exert a variable counterpoising force as opposed to the weight of the arm 5 and the parts carried thereby as it is moved from side to side of the machine. 105 With the arm 5 in the position as shown in Fig. 1 the flexible member 6 has caused the upper arm of the compensating lever 12 to

swing to the right-hand side of a vertical line and carry the outer end of the other arm below a horizontal line, and the link 14 being connected to the lever 12 intermediate its ends, 5 as shown in Fig. 1, the effective length and force of lever 12 upon the link to draw it toward the right hand of the machine increases as the lower arm of the lever moves downward, and the opposite end of link 14 being 10 connected, by means of the flexible members 20 and 21, with the counterbalancing-springs 29 they are thereby extended in length and are operative to carry the load connected therewith. When the arm 5 is being moved 15 from the position shown in Fig. 1 to that shown in Fig. 2, the springs 29 exert a variable power as they contract, which is compensated for by the decreasing effective length of the arm of lever 12, to which the 20 flexible member 6 is connected, as it swings toward the left-hand of the machine and upward, as shown in Fig. 2.

In operating machines of this class the pattern is usually made in two parts that are secured to opposite sides of the arm 5. A part 25 of the flask is secured to the arm in a manner to inclose one-half of the pattern, and after it has been filled with sand in the usual way the arm is swung to the opposite side of the bed-frame and the flask will rest thereon. The 30 means for securing the flask to the arm are then released and the pattern is withdrawn and the arm swung back again, leaving the half-flask supported upon the bed-frame, and 35 these movements may be repeated and the flask may be secured to either side of the arm desired, the object of the spring-counterbalancing mechanism being to counterpoise the weight of the arm and flask at any point in 40 their movement for the purpose of preventing sudden jars that would tend to destroy the mold and to make the operation of molding and handling the flask less laborious.

What I claim as being my invention, and 45 desire to secure by Letters Patent, is—

1. In a molding-machine, the combination 50 of a bed-frame, a pattern-carrying arm mounted upon a horizontal pivot upon said frame and adapted to swing from a vertical to a horizontal position in either direction, a counterbalancing mechanism comprising a flexible member connected with said arm upon one side of said pivot and extending 55 downward and engaging with a sheave below said pivotal connection of the arm, and approximating one hundred and eighty degrees, a counterbalancing mechanism comprising a flexible member connected with said arm upon one side of said pivot and extending downward and engaging with a sheave below said pivotal connection of the arm and extending outward and engaging with a sheave mounted at one end of said frame and then inward and connected to one 60 end of a lever pivotally mounted at its opposite end upon the frame, a flexible member connected with said lever intermediate its ends and extending outward and engaging with a sheave at the opposite end of said frame and then inward and connected to one 65 end of a counterbalancing-spring, said spring

having its opposite end secured to the frame at the first-mentioned end thereof.

2. In a molding-machine, the combination 70 of a bed-frame, a pattern-carrying arm mounted upon said frame in a manner permitting it to swing in a vertical plane to a horizontal position in either direction from the vertical, a counterbalancing mechanism connected therewith comprising a two-armed compensating lever, said arms disposed at 75 substantially right angles with each other, one arm at its outer end pivotally connected with the frame and extending downward therefrom at substantially right angles with the horizontal plane thereof when said pattern-carrying arm is in a vertical position, the other arm having openings at opposite 80 ends thereof, flexible members connected with said openings and extending outward in opposite directions therefrom, said members 85 engaging with sheaves mounted on the frame and extending inward therefrom and having one member connected with the pattern-carrying arm and the other member connected with a counterbalancing-spring in a manner 90 to operate as a counterpoise for the weight of said pattern-carrying arm.

3. In a molding-machine, the combination 95 of a bed-frame, a pattern-carrying arm mounted upon a horizontal pivot upon said frame and adapted to swing from a vertical to a horizontal position in either direction, a counterbalancing mechanism comprising a flexible member connected with said arm upon one side of said pivot and extending 100 downward and engaging with a sheave below said pivotal connection of the arm, and extending outward and engaging with a sheave mounted at one end of said frame, and then inward and connected to one end 105 of a lever having its opposite end pivotally connected with the frame, a link pivotally connected at one end with said lever intermediate its ends, said link having a cross-head at its opposite end, flexible members 110 connected with opposite ends of said cross-head and extending outward toward the opposite end of said frame and engaging with sheaves mounted thereon, and then extending inward and secured to one end of coiled 115 counterbalancing-springs having their opposite ends secured to the frame at the first-mentioned end thereof.

4. In a molding-machine, the combination 120 of a bed-frame, a pattern-carrying arm mounted upon a horizontal pivot upon said frame and adapted to swing from a vertical to a horizontal position in either direction, a counterbalancing mechanism comprising a flexible member connected with said arm 125 upon one side of said pivot, and extending downward and engaging with a sheave below said pivotal connection of the arm, and extending outward and engaging with a sheave mounted at one end of said frame, 130

and then inward and connected to one end of an elbow-lever having its opposite end pivotally connected with the frame, the connecting means comprising a link having upturned 5 ends, one of which is connected to said elbow-lever and the opposite end to one end of a turnbuckle having its opposite end connected with said flexible member, a link pivotally connected at one end with said elbow-lever intermediate its ends, said link having a cross - head at its opposite end, flexible members connected with opposite ends of said cross-head and extending outward toward the opposite end of said frame and en-

gaging with sheaves mounted thereon, and 15 then extending inward and adjustably connected to one end of coiled counterbalancing-springs, said adjustable connections comprising threaded eyebolts connected with the flexible members, and threaded nuts engaging 20 with the coils of the springs and having said eyebolts engaging with said nuts.

In witness whereof I hereto affix my signature in presence of two witnesses.

CLINTON A. HAGADONE.
